UNITED STATES PATENT OFFICE.

FEARGUS O. GINNEVER, OF LOS ANGELES, CALIFORNIA.

CORSET.

No. 913,883.

Specification of Letters Patent. Patented March 2, 1909.

Application filed October 25, 1904. Serial No. 5229,394.

To all whom it may concern:

Be it known that I, FEARGUS O. GINNEVER, a citizen of the United States, residing at Los Angeles, in the county of Los Angeles, State of California, have invented certain new and useful Improvements in Corsets, of which the following is a specification.

The main object of this invention is to provide a corset which will yield or adapt itself to the figure without undue pressure on any part and without interfering with the movement of the parts.

A further object of the invention is to provide a corset of material that will be sufficiently open to give a cool ventilated garment.

A further object of the invention is to provide a corset that is particularly adapted to calisthenic exercises, permitting free movement of the body.

The accompanying drawings illustrate the invention.

Figure 1 is a general view showing the corset in position on the figure. Fig. 2 is an inside or rear view of one side of the corset. Fig. 3 is a front or outside view of the other side of the corset. Fig. 4 is a detail view showing the weave of the elastic fabric.

The corset comprises two members 1 of identical construction and reversely or symmetrically shaped in such manner that when laced together they will form a complete corset. Each of said members comprises end stays 2, 3, respectively at the front and rear ends thereof, the rear strips 3 being provided with eyes 4 for the reception of lacing in the usual manner, and the front strips being provided with snaps for attaching means, 5, 6. Connecting these end strips 40 is a web or sheet 7 of elastic fabric which narrows toward the middle between the end stays 2, 3, and is so woven as to admit of endwise distention or yielding of the corset member, as well as bending or protrusion of any portion thereof. The weave of this elastic fabric may be as shown in Figs. 2 and 3, the foundation or backing 8 of the fabric being formed of elastic thread,—that is to say,—thread having a core of rubber, the general direction 50 of these threads being longitudinally from the front to the back of the corset, but the threads diverging at each end to correspond to the divergence or widening of the corset.

To secure this divergence the thread is looped 55 or turned on itself at intervals as indicated

af 9, so as to give short weave elements extending only partially from the end toward the center of the fabric and intruding between the complete longitudinal thread elements to give the necessary divergence thereof. This backing is woven into or on to a fabric consisting of knitted or diagonal or bias threads or weaving indicated at 10 in Fig. 3, this diagonal knitting or weaving being the portion that appears at the front or outside of the corset. This diagonal knitting or weaving allows free stretching of the elastic foundation of the fabric with the result that the corset will give in such manner as to conform to the shape of the figure 70 in an easy manner, and without undue pressure. The knitted or woven fabric being open in texture gives a cool, ventilated garment. Additional stays 12 may be secured to the fabric between and parallel to the end 75 stays 2, 3, these intermediate stays being preferably more flexible than the end stays so as to yield more readily in the bending or curvature of the corset to the body.

The lower and upper selvages or edges of 80 the elastic fabric are more closely woven than the intermediate portion 15, so that the backing shown in Fig. 2 is composed of fabric having elastic threads for extending around the body and arranged in three bands 13, 14, 85 15, the latter of which is more open and consequently more elastic than the former. By this construction an easier-fitting garment and one that permits free movement for calisthenics and the like, is provided. By 90 reason of the corset being narrowed between the end stays 2 and 3, the lower edge thereof does not bind at the sides of the body adjacent to the hips, as will be more fully understood from Fig. 1, which illustrates the 95 smooth fit of the corset to the body of the wearer.

What I claim is:

1. A corset comprising end stays and elastic fabric connecting the same, consisting 100 of a foundation of longitudinally-disposed elastic threads woven together with diagonal threads, said longitudinally-disposed elastic threads being arranged to extend around the body of the corset.

2. A corset comprising end stays and elastic fabric connecting same, said fabric being diagonally woven and having a foundation of elastic threads disposed longitudinally 105 of the fabric to extend around the body of 110

the corset, and having return loop portions extending from the ends thereof towards the center.

3. A corset provided with end stays, a body portion formed on one side of diagonally-woven backing connecting said stays, and on the other side of elastic threads extending around the body of the corset.

In testimony whereof, I have hereunto set my hand at Los Angeles, California this 14th 10 day of October 1904.

FEARGUS O. GINNEVER.
